EARL C. ALEXANDER, OF CHICAGO, ILLINOIS, ASSIGNOR TO MASSEY CONCRETE PRODUCTS CORPORATION, OF CHICAGO, ILLINOIS, A CORPORATION OF VIRGINIA.

CRIBBING.

Application filed May 23, 1925. Serial No. 32,249.

The present invention relates to cribbing, such as is used in the construction of retaining wall, railway embankments, piers, etc.

One of the objects of the invention is to provide cribbing comprising a particular construction and arrangement of stretchers and interlocking headers in which the outer faces of the interlocking headers lie substantially flush with the outerfaces of the headers. There is thereby provided a relatively smooth cribbing wall unbroken by projecting ends or heads. The projection of these ends or heads of the headers from the surface of the wall is objectionable, as these projecting portions reduce the permissible over-all width of the cribbing where space is an important factor. Furthermore, they do not provide a neat appearing construction and are objectionable for other reasons. It is a further object of the invention to provide a construction of cribbing in which the headers interlock the stretchers against longitudinal shifting movement, and also interlock the stretchers against outward displacement from the cribbing wall.

A further object is to provide a construction of cribbing utilizing stretchers and headers of comparatively simple sectional form in which the cost of molding and reinforcing by suitable metal reinforcement is reduced to a minimum.

Referring to the accompanying drawing, wherein I have illustrated a preferred embodiment of my invention—

Figure 1 is a front elevational view of cribbing constructed in accordance with my invention;

Figure 2 is a vertical sectional view through the cribbing or wall shown in Figure 1;

Figure 3 is a perspective view of the ends of the stretchers and headers showing the relation of their assembly.

Referring now to the drawings, in which like reference characters indicate like parts in the several views, 10 indicates the headers, which are all of the same character, and 12 indicates the stretchers. Different forms of stretchers may be employed in the front and rear tiers of the cribbing, if desired, but I find that the one standard design of stretcher, hereinafter described, is suitable for both the front and rear tiers, and standardizes the parts.

The headers 10 are substantially rectangular in cross section, as illustrated in Figure 3, and are provided at each end thereof with T-shaped heads 14 consisting of upwardly and downwardly extending shoulders or flange portions 15. These T-shaped end portions 15 extend to a depth substantially equal to one-half of the vertical height of each stretcher 12. The reverse sides of these T-shaped portions 15 are sloped, as indicated at 16, to facilitate assembly and to get the necessary strength to the portions 15. The longitudinal body portions of the headers 10 are suitably reinforced by rods or wires 18, preferably disposed adjacent the corners of the headers, as shown in Figure 3, and this reinforcing may be extended upwardly and downwardly into the T-shaped end portions 15, if desired. However, by virtue of sloping the reverse sides of these projecting portions 15, as indicated at 16, the extension of this reinforcing into these projecting end portions 15 is not essential because of the additional thickness of these end portions where they join with the longitudinal portion. It will be evident that this form of T-shaped head can be molded with ease in a relatively inexpensive form of mold because of the absence of all lateral projections on the header. Both ends of each header are, of course, similar in construction and arrangement, having the same form of T-shaped end portions 15—15 provided with sloped inner walls 16.

The stretchers 12 are preferably rectangular in cross section throughout their length, as illustrated in Figure 3. At their ends these stretchers are formed with rabbets or notches 21 recessed in their front faces. These rabbets or notches 21 extend inwardly to a depth approximately equal to one-half the thickness of the stretcher leaving interlocking tongue portions 22 extending from the ends of the stretchers. These extending tongue portions 22 are of ample thickness to leave the requisite strength for interlocking the stretchers against outward displacement under the pressure of the dirt and filling material pressing outwardly on these stretchers. The notches or recesses 21 have a longitudinal depth equal to approximately one-half of the crosswise thickness of the headers 10. These stretchers 12 are reinforced by any suitable reinforcing rods or wires 24 and, if desired, the reinforcing rods or wires located adjacent the inner sides of

the stretchers may be extended into the projecting tongue portions 22. It will be understood that the opposite ends of the stretchers 12 are similar in construction and arrangement, both having the notches or rabbets 21 formed in their outer faces.

In constructing a retaining wall such as shown in Figure 2, a front and rear series of stretchers 12 are first laid upon the ground with the end tongues 22 substantially contacting end to end between the stretchers. In order to obtain the proper inclination of the completed retaining wall where such is desired, the rear series of stretchers 15 is disposed on a lower plane than the front series of stretchers. Upon these series of stretchers are then placed the headers 10, the lower T-shaped end portions 15 being set into the adjoining recesses 21 in the ends of the stretchers. Upon this series of headers is then placed another tier or layer of stretcher bars, the end tongues 22 of the stretcher bars being placed behind the upwardly extending T-shaped end portions 15 of the header bars. This process is continued, placing the stretchers on top of the headers, and the headers on top of the stretchers, in much the same manner a rail fence might be constructed, until the wall has reached its required height. Due to the simple character of the header and stretcher bars the wall may be readily constructed by unskilled workmen, and in fact, may be readily constructed by a single workman if the individual bars are made of such a size that one man can handle them. Where the wall is to be extended up to a considerable height, a secondary or supplemental course of headers and another course of stretchers may be provided at the rear of the first course for reinforcing and supporting the first course in the process of construction. After this construction of cribbing has been erected, the wall or embankment is filled in with dirt, gravel or any other filling material which serves to bind all of the header and stretcher bars together.

It will be noted from Figures 2 and 3 that the engagement of the T-shaped end portions 15 in the recesses 21 of the adjoining stretchers will interlock the headers to the stretchers to prevent outward displacement of the stretchers under the pressure of the filling material, tending to force the stretchers outwardly. It will also be noted that the abutment or substantial abutment of the shoulder 21' at the end of each notch or recess 21 against the lateral face of the T-shaped end portion 15 will interlock the stretchers 12 against any longitudinal shifting movement relative to the headers. There are necessarily certain discrepancies introduced in the erection of cribbing of this type, and particularly the spacing between the front and rear courses of the stretchers as the cribbing progresses. The

sloped rear sides 16 tend to alleviate difficulties which might arise in this regard, as these sloping sides enable the ends of the T-shaped portions 15 to be dropped into the recesses 21 where the spacing between the front and rear stretchers of the uppermost layer somewhat exceeds the intended spacing between the stretchers. The sloped rear sides 16 enable these T-shaped end portions 15 to be started in the adjoining recesses 21, and thereafter, the weight of the headers and the successive tiers of stretchers will force the sloped rear walls downwardly along the forward edges of the extended tongue portions 22 until the stretchers rest upon the upper surfaces of the stretchers.

It will be observed from Figures 2 and 4 that after the cribbing is completed all of the T-shaped end heads 14 of the stretchers lie in the recesses 21 of adjoining stretchers and there are no projections protruding from the face of the cribbing.

Having thus described my invention, what I claim is:

1. A cribbing structure comprising a plurality of headers having T-shaped ends and having flat sides, and a plurality of stretchers of rectangular shape lying transversely and alternately on said headers and having sufficient of the ends of said stretchers removed to form a complementary space for receiving said T-shaped ends.

2. A cribbing structure comprising a plurality of headers having rectangular cross-section, T-shaped ends and flat sides, and a plurality of stretchers of rectangular shape lying transversely and alternately on said headers and having sufficient of the ends of said stretchers removed to form a complementary space for receiving said T-shaped ends.

3. A cribbing structure comprising a plurality of headers having T-shaped ends and flat sides, and a plurality of stretchers of rectangular shape abutting each other, end to end, and having an outer portion of ends of said stretchers removed to form a complementary space for receiving said T-shaped ends, said headers and stretchers being laid alternately and transversely upon each other.

4. A cribbing structure comprising a plurality of headers having flat top and bottom bearing surfaces at each end, transversely projecting end portions and flat sides, said end portions being vertically disposed, and a plurality of stretchers having bottom and top flat bearing surfaces co-operating with the said header bearing surfaces, said stretchers abutting each other end to end and presenting a front surface flush with the ends of said headers.

5. A cribbing structure comprising a plurality of headers having flat top and bottom

bearing surfaces at each end and transversely projecting end portions of rectangular cross-section decreasing in size toward their ends, said end portions being vertically disposed and said headers having flat sides, and a plurality of stretchers having bottom and top flat bearing surfaces co-operating with

the first named bearing surfaces, said stretchers abutting each other end to end and presenting a front surface flush with the ends of said headers.

In witness whereof, I hereunto subscribe my name this 19th day of May, 1925.

EARL C. ALEXANDER.
